(57) **CLAIM**

I claim the ornamental design for an interior and exterior surface of a fence panel, as shown and described.

DESCRIPTION

FIG. 1 is a perspective view thereof;

FIG. 2 is a front view thereof;

FIG. 3 is a rear view thereof;

FIG. 4 is a right side view thereof;

FIG. 5 is a left side view thereof;

FIG. 6 is an upper end view thereof; and,

FIG. 7 is a lower end view thereof.

The portions of the figures shown in broken lines are for illustrative purposes only and form no part of the claimed design. The drawings depict the design of a fence panel, and no limitations on length or size are intended thereby.

1 Claim, 3 Drawing Sheets
